UNITED STATES PATENT OFFICE.

ELIHU THOMSON, OF SWAMPSOFT, MASSACHUSETTS, ASSIGNOR TO GENERAL ELECTRIC COMPANY, A CORPORATION OF NEW YORK.

REGULATOR FOR INCLOSED ELECTRICAL APPARATUS.

Application filed October 11, 1923. Serial No. 667,952.

To all whom it may concern:

Be it known that I, ELIHU THOMSON, a citizen of the United States, residing at Swampscott, in the county of Essex, State

5 of Massachusetts, have invented certain new and useful Improvements in Regulators for Inclosed Electrical Apparatus, of which the following is a specification.

The present invention comprises an electrical apparatus which is inclosed in a sealed receptacle and which is provided with electromagnetic means whereby a desired regulating or controlling effect is exerted through the wall of the container 15 from the exterior.

My invention is applicable in particular to the regulation of electron discharge apparatus, such as inclosed X-ray devices. For example, in Coolidge and Wagner Patent 20 No. 1,394,144 is described an X-ray apparatus comprising an X-ray tube immersed together with a transformer in a body of oil contained in a sealed tank, a ratchet operated rheostat being provided in the tank 25 adjustable through a flexible diaphragm in the wall of the tank.

In accordance with my present invention I have provided an X-ray outfit in which one member of a regulating outfit is located 30 fixedly within a tank together with the X-ray tube and related parts, and means being provided whereby the electrical characteristic of this regulating outfit may be inductively varied through the container wall 35 by an external device thereby avoiding all sealed moving parts which are liable to get out of order.

My invention is not limited in its application to X-ray devices but to any devices in which a magnetically responsive 40 member is placed within a sealed inclosure and acted upon by another magnetic member located on the outside of the inclosure.

In accordance with my invention, the 45 magnetic member inside of the sealed receptacle is acted upon by the exterior member through a non-magnetic wall, means being provided to vary the inductive relation of the exterior and interior members to 50 produce a desired regulation. For example, in the case of the X-ray apparatus of the type to which reference has been made above, the X-ray cathode contains an inductance coil mounted within the tank and 55 the inductance value of the coil is varied

by an external regulator which has no physical connection with the inductance coil in the tank, but which is magnetically linked therewith.

In the accompanying drawings, Fig. 1 is 60 a vertical section of an X-ray apparatus as a whole to which my invention is applicable; Fig. 2 is a vertical section of the same showing the mechanical arrangement of the coil and core; Figs. 4 and 6 are diagrammatic 65 representations of electrical circuits; Figs. 3, 5, 7 and 8 are detailed views of structural features and modifications of my invention.

The X-ray outfit embodying my invention shown in Figs. 1 and 4 comprises a tank 1 70 containing a transformer 2, and an X-ray tube 3 which is connected to the transformer secondary 4 by the conductors 5, 6. The X-ray tube 3 is provided with a cathode 7 which is capable of being rendered incandescent by a current derived from an auxiliary heating transformer 8, connected thereto by the conductors 9, 10. The X-ray tube is mounted conveniently by insulating supports 11, 11' upon the cover 12. The 80 contained apparatus is immersed in oil as indicated by dashed lines. The tank cover (which may consist of hard rubber or fibre) is bolted to make an oil tight seal. The X-ray tube has been indicated diagrammatically for the sake of simplicity, but it is to be understood that the X-ray tube is of the pure electron type, such as described in Coolidge Patent No. 1,203,495.

Included in the cathode heating circuit is 90 an inductance coil 13 whereby the current in the heating circuit and hence the temperature and electron emission of the cathode may be regulated in order to regulate the X-ray output.

As shown in Fig. 2 this inductance coil 13 is mounted upon a thin tube 14 of non-magnetic and preferably high resistance material, as for example, a non-magnetic steel containing 12% or more of manganese or nichrome alloy or any other high resistance metal which is adapted to make a tight joint with the main portion of the receptacle. The core 15 is movable from the exterior into this tube 14, the core being conveniently mounted upon a screw 16 passing through a threaded support 17 which is attached to the main container 1.

In order to avoid eddy currents in the casing surrounding the core a magnetic shunt 110

19 is provided on the interior of the casing. This shunt may consist of a set of thin iron plates mounted upon the tube 14 within the casing. As shown in Fig. 3 these ring-shaped plates or washers are split to avoid the induction of eddy currents surrounding the core. When it is desired to vary the incandescence of the cathode 7, thereby varying the current through the X-ray tube and thus the intensity of the X-ray emitted from the X-ray tube, the core 15 is moved outwardly so as to be withdrawn from the coil 13, thereby reducing the reactance of the cathode circuit 9, and thus increasing the heating current in the circuit. Conversely, when the X-ray output is to be reduced, the core 15 is moved inwardly into closer magnetic linkage with the coil 13, thereby reducing the heating current by reason of the increased reactance of the cathode circuit. In some cases the core may have a bipolar shape or horseshoe shape as shown in Fig. 5.

In the modification of my invention illustrated in Figs. 6, 7, and 8 both the internal and the external inductive coils 21, 22 are of the pancake type. As diagrammatically shown in Fig. 6 the external coil 22 consists of two parallel wires or ribbon conductors which are provided with a plurality of taps 30 leading to the insulated segments of a commutator 23 numbered consecutively from 1 to 12 as indicated. Brushes 24, 25 are mounted upon fixed resilient supports 26, 27 whereby connection is made to the conductors 28, 29 leading to secondary of a transformer 35. The primary of this transformer receives current from the main supply conductors.

The commutator 23 and the coil 22 which consists of a double wound conductor, are fixedly connected to a hand wheel 31 and together are connected to a rotatable shaft 32 which in turn is mounted on the wall of the tank as indicated in Fig. 7. By turning the commutator by the hand wheel 31 the effective number of turns of the coil 22 may be varied from a maximum when the brushes 24, 25 bear on the segments 1 and 7 as shown in Fig. 6 to a minimum when the brushes 50 bear on segments 4 and 10. In the latter case, the current divides in opposite directions through the double conductors and thus substantially neutralizes the magnetic effect. Hence the inductance value of the coil is varied accordingly, the two coils 21, 22 being magnetically linked and being traversed by alternating currents substantially in phase. By means of the hand wheel the coil 22 may be rotated from a position giving a maximum boosting effect for a high cathode temperature through a neutral position to a position giving a maximum bucking effect for a minimum cathode temperature.

In some cases, the winding 22 may be used 60 as a short-circuited secondary without ex-

ternal excitation. This has been indicated by the circuit 33 shown in dotted lines. The switch 34 to the transformer 30 is assumed to be open and the switch 35 closed when thus using the apparatus. In that case when the commutator is in the position shown in Fig. 6, the coil of two parallel wires is short-circuiting, thus forming a closed secondary and increasing the current in the coil 21 by neutralizing in part its self-induction. When the commutator is turned one-fourth revolution the two halves of the coil 22 are opposed, and there is no current in the coil, thereby decreasing the current in the coil 21.

What I claim as new and desire to secure by Letters Patent of the United States, is:—

1. An electrical apparatus comprising a sealed tank, an electrical discharge device contained therein and a regulator for said device having cooperating members, one being fixedly located within said tank and another being located external to said tank in variable inductive relationship to said internal member.

2. An electrical apparatus comprising a sealed tank, a discharge tube located therein, having a cathode operable at incandescence, means in said tank for furnishing a heating current to said cathode, and a circuit external to said tank containing means for varying the inductance of the heating circuit within said tank.

3. An X-ray device comprising a sealed tank, an incandescent cathode X-ray device therein, a heating circuit therefor, and a regulator for said circuit having cooperating members one of which is sealed within said tank, adjacent the non-magnetic wall member, the other being external thereto and being inductively related to said internal member.

4. An X-ray apparatus comprising a tank, an incandescent cathode device therein, means in said tank for heating the cathode of said device, an inductance coil in said tank in circuit with said means, and an inductive regulator for said coil located external to said tank and linked by a magnetic field with said coil.

5. An electrical device comprising a receptacle containing a wall section of non-magnetic material, coacting magnetic members one of which is located fixedly within said container on the inner side of said non-magnetic section, and the other being located on the outside of said section, and means for varying the magnetic relation of said members.

6. An electrical device comprising a receptacle containing a wall member of non-magnetic material, coacting magnetic members one of which is located fixedly within said receptacle on one side of said wall member, the other member being located externally and in magnetic relation to said first

member, and switching means for varying the effective magnetizing value of said external member.

7. An electrical device comprising a sealed tank, an electrical discharge device contained therein having a cathode operable at incandescence, circuit connections in said tank for furnishing an alternating current to said cathode, an inductance coil in said heating circuit, an external inductance coil in induc-

tive relation thereto, a commutator having connections to different sections of said winding, and means connected in adjustable relation to said commutator for furnishing an alternating current in phase with said heating current. 15

In witness whereof, I have hereunto set my hand this 6th day of October, 1923.

ELIHU THOMSON.
